GAME BOARD AND APPARATUS FOR USE
THEREWITHFreeman R. Stearns, Ludington, Mich., assignor
to The Carrom Company, Ludington, Mich., a
corporation of Michigan

Application September 27, 1937, Serial No. 165,878

4 Claims. (Cl. 273—89)

This invention relates to improvements in game boards and apparatus for use therewith.

The main objects of this invention are:

First, to provide a new and improved game board suitable for use in playing a game closely simulating baseball.

Second, to provide a board of the type described and apparatus for use therewith facilitating play.

10 Third, to provide a game board having indicia thereon for use in playing a game closely simulating baseball, the said indicia being printed or otherwise impressed on one side of the board and the other side thereof having provisions whereby another game may be played on that side.

Fourth, to provide a board of the type described suitable for playing a game using a number of missiles or rings, the latter sliding on the 20 surface of the board and simulating various plays in baseball.

Fifth, to provide a game board and apparatus for use therewith, said apparatus being in the form of a projecting device for propelling or 25 sliding missiles or rings along the surface of the board.

Sixth, to provide a projecting device of the type described which is so constructed as to guide and expel rings or other missiles, at the 30 same time restraining the same from movement in any direction other than a desired direction and in sliding relation to the surface of the game board.

Seventh, to provide a board embodying a novel 35 and approved type of bat or propelling apparatus adapted to be manually operated by a player.

Eighth, to provide a bat or propelling apparatus for use in connection with a board of the type described.

40 Further objects and advantages pertaining to details and economies of construction and operation will appear from the description to follow. The invention is pointed out in the claims. A preferred embodiment of the invention is illustrated in the accompanying drawing, in which:

Fig. 1 is a view of the board of the invention illustrating the markings thereon for use in playing a game closely simulating baseball.

Fig. 2 is a perspective view illustrating a projecting or throwing device which I have devised 50 for use in playing the game, the manner of using said device likewise being indicated.

Fig. 3 is a horizontal sectional view through the throwing device illustrating details of the 55 construction thereof.

Fig. 4 is a perspective view of a missile or ring which is used in playing the game, the same performing, in the game, the functions of a baseball.

Fig. 5 is a perspective view of a peg such as 5 may be used in connection with the board of the invention for keeping score or recording the number of outs.

Fig. 6 is a fragmentary view in section on line 6—6 of Fig. 1 illustrating details of the pocket 10 construction of batting mechanism found in the board of the invention.

This invention relates to game apparatus, more particularly to game boards such as the type which have been used in playing games 15 involving the shooting of a missile along a polished surface bounded by retaining walls. The games of "Carroms" and "Crokinole" are illustrative of this type of game. It is the object of the present game and the structure with 20 which it is played to simulate not only the physical markings of a baseball field, but also to simulate the playing procedure of the game of baseball.

Referring to the drawing, the reference number 1 in general indicates a board or panel of plywood or other suitable material having smoothly finished upper and lower surfaces which are bounded on four sides by the border walls 2. Segments are cut from the corners of 30 the panel to provide openings 3 across which netting 4 is secured to provide pockets for receiving the playing pieces or missiles. The surface 1 has printed or otherwise marked thereon a number of areas of different size and color. For 35 instance, adjacent the retaining walls 2 are provided a number of rectangular green areas 5 arranged side by side and separated by dividing lines 6 of white or natural color. Just inside of this outermost zone there is a series of 40 rectangular areas 7 which are preferably natural or white in color and separated by green lines 8, and inside the last named series of areas, I provide a square area 9, divided by the white line 10 and the white diagonal area 11 into four 45 triangular areas 12 which are colored green. The said diagonal area is itself divided by green lines into three separate areas.

Of course, the coloring of the respective areas is unimportant and the same may be altered in 50 any manner. The size of the areas likewise may be altered if desired.

Aside from being colored in one way or another, each of the areas carries designations indicating one or another sort of play occurring 55

in the game of baseball. For instance, the areas 5 each bear the word "Actual" along with information as to the type of play made when a missile, rebounding from the bat in a manner 5 to be described, comes to rest therein. Each of the areas 7 is designated by the words "Fielding play", indicating that a fielding play is in order when a missile comes to rest in one of those areas. The other areas are similarly 10 designated.

At one of the corners of the board, I pivot a batting or propelling device consisting of a metal strip 13 freely pivoted at 14 to the border wall 2 and provided with an upstanding handle 15 15 adapted to be grasped by a player for angular manipulation into the path of a pitched ball or missile projected by a device to be hereinafter described. The strip 13 carries a pair of depending stops 16 adapted to engage the border 20 wall 2 to limit the angular movement of the bat and the free end of the bat is provided with a depending spring steel finger 17 adapted to be struck by the missile in play whereby to cause 25 the missile to rebound in the direction from which it came, in the manner of a batsman batting a ball. The strip 13 rests on and is guided by an arcuate wire element or other suitable support indicated by the reference numeral 171 and having offset ends 172 fitting apertures in 30 the retaining walls 2 to mount the guide on the board.

The batting device is essentially characterized by the fact that only the rebound of the missile therefrom is relied upon to motivate the 35 same. No initial or additional impetus is imparted to the missile by the bat other than the spring rebound of the missile therefrom.

The missile may take the form of any object 40 capable of sliding freely on the surface of the board 1, but I preferably form the same as a ring or annulus 18. I provide a number of these missiles in various colors.

For the purpose of projecting the missile toward the bat or propeller 13, I provide a projecting device generally indicated by the numeral 45 19, said device being a block suitably shaped for ready grasping in the hand of a player, and preferably of oval form. The block is medially slotted at 20 to provide an elongated channel on 50 the side thereof adjacent the board when the projecting device is in operative position during play. The said channel is overhung on the upper side of the block by elongated shoulders 21 serving to horizontally guide the player's finger, which is inserted in the hole of the missile, 55 to prevent upward movement of the missile and to form a path along which the same is projected outwardly by means of a rubber band 22 surrounding the block below the said shoulders. 60 A peripheral channel 23 around the side of the block provides a means for locating the rubber band to prevent displacement thereof and to insure that the band engages the missile at its center. The shoulders 21 are continued outwardly beyond the rubber band 22 as indicated 65 at 24. Slot 20 is made sufficiently long so that the player is afforded an opportunity to shoot the missiles with any desired speed. It will be appreciated that the annular form of the missile 70 considerably facilitates the operation of the projecting device by allowing the player's finger to be inserted therein in order to retract the missile against the band.

The manner of using the projecting device is 75 illustrated in Fig. 2. The ring 18 is retracted in

the channel 20 against the projective force of the rubber band by means of the player's finger and upon being released is rapidly projected outwardly from the channel across the surface of the board. The projectiles may be projected by 5 snapping with the fingers.

The game may be played by two persons, each representing a side, one of whom manipulates the projecting device 19 and the other of whom acts as a batter by manipulating the propelling device 15 in an arc transversely of the path of travel of the missile projected by the device 19. It is the object of the person pitching or manipulating the device 19 to strike out the batsman by shooting the rings past the bat, the rings being shot for this purpose from the point 25 on the board designated by the words "Actual home run". Of course, the rules for play may be varied and, as a matter of fact, form no part of the invention, but the board has been particularly designed to facilitate playing a game closely following the rules of baseball. In other words, if the batsman returns a pitched ball to any of the areas marked "Actual", then he is credited with having made a play as indicated on that area. 10 If the missile comes to rest on an area marked by the words "Fielding play", then it is the turn of the pitcher to determine the nature of the fielding play by endeavoring to strike the batsman's missile with a special black fielding missile, first causing the fielding missile to "carrom" off one of the retaining walls 2 adjacent the batting device. Score is kept as in baseball and I have provided a series of holes 26 in one of the retaining walls to receive suitable pegs 27 for 15 this purpose. Likewise, openings 28 in another retaining wall are provided to receive similar pegs for the purpose of keeping count of the 20 number of outs.

The pockets 14 to the left and right of the 40 batting device and directly opposite the same may be used to receive missiles batted therein. In case the batsman rebounds the missile or ring into any one of the pockets to right or left of or opposite the batting device, he is credited 45 with having made a single or a home run as the case may be, as designated on the board. The fourth pocket underneath the batting device serves to receive missiles or rings passing by the 50 batting device.

It will be apparent that these pockets 14 are likewise of value in playing any desired game for which the reverse side of the board lends itself. For instance, the game of baseball as played on the surface in the manner just described may be combined with a surface adapted for playing "Carroms" or for playing "Crokinole" or for 55 playing any other suitable game.

I have devised the projecting device 19 particularly for use in connection with the baseball game above described. However, it will be apparent that its field of application is not necessarily limited to that game and it may be employed in any similar game calling for the projection of a missile across a polished surface. Likewise, the batting device which is manipulated in an arc transversely of the path of the pitched missile may be utilized in connection with other types of baseball or similar games.

I have illustrated and described my improvements in an embodiment which I have found highly satisfactory. I have not attempted to illustrate or describe other embodiments or adaptations as it is believed that this disclosure will 75

enable those skilled in the art to embody or adapt my improvements as may be desired.

Having thus described my invention, what I claim as new and desire to secure by Letters Patent, is:

- 5 1. In combination, a rectangular game board having a smooth playing surface surrounded by a retaining wall, said surface having indicia impressed thereon for use in playing a game closely simulating baseball, and a one-piece batting or propelling device pivotally mounted on said retaining wall at one corner thereof and movable angularly equal distances on both sides of a line diagonal of the board and extending through 10 said corner to intersect the path of a missile traveling toward the device, said device having angular stops adapted to engage said wall to limit the angular movement thereof, and a depending finger of 15 spring metal at the free end of said device for causing a missile striking the finger to rebound therefrom, and an arcuate guide rail connected at 20 its ends to said retaining wall for guiding and slidably supporting the device during angular movement thereof.
- 25 2. In combination, a rectangular game board having a smooth playing surface surrounded by a retaining wall, said surface having indicia impressed thereon for use in playing a game closely simulating baseball, and a one-piece batting or propelling device pivotally mounted on said retaining wall at one corner thereof and movable angularly equal distances on both sides of a line diagonal of the board and extending through 30 said corner to intersect the path of a missile trav-

eling toward the device, said device having angular stops adapted to engage said wall to limit the angular movement thereof, and an arcuate guide rail connected at its ends to said retaining wall for guiding and slidably supporting the device 5 during angular movement thereof.

3. In combination, a rectangular game board having a smooth playing surface surrounded by a retaining wall, said surface having indicia impressed thereon for use in playing a game closely 10 simulating baseball, and a one-piece batting or propelling device pivotally mounted on said retaining wall at one corner thereof and movable angularly equal distances on both sides of a line diagonal of the board and extending through 15 said corner to intersect the path of a missile traveling toward the device, and an arcuate guide rail connected at its ends to said retaining wall for guiding and slidably supporting the device during 20 angular movement thereof.

4. In game apparatus of the type described, in combination, a game board having a smooth surface provided with indicia for use in playing a game simulating baseball, said board having a retaining wall surrounding the same, a batting 25 device comprising a member pivotally mounted to the game board and adapted to be moved in an arc transversely of the path of movement of a missile approaching the device, said path being substantially normal to said arc, and an arcuate 30 guide element beneath said member to support and guide the same for pivotal movement.
